(57) **CLAIM**

The ornamental design for a handle of hand tool, as shown and described.

DESCRIPTION

FIG. 1 is a perspective view of a handle of hand tool;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a sectional view taken along line 8-8 of FIG. 5;

FIG. 9 is a sectional view taken along line 9-9 of FIG. 5; and,

FIG. 10 is a perspective view of a hand tool thereof, the only difference being the broken lines. The broken line showing of environmental structure is for illustrative purposes only and forms no part of the claimed design.

1 Claim, 6 Drawing Sheets(56)
